(57) **CLAIM**

The ornamental design for a portion of a container, as shown and described.

DESCRIPTION

FIG. 1 is an exploded perspective view of a portion of a container showing my new design, where the lid is shown in a closed state;

FIG. 2 is an exploded perspective view thereof, where the lid is shown in an open state;

FIG. 3 is a front unexploded view of FIG. 1;

FIG. 4 is a rear view thereof;

FIG. 5 is a right side view thereof, the left side view being a mirror image; and,

FIG. 6 is a top view thereof.

The lid is shaded to indicate a translucent material. The translucent material can be a variety of colors.

The dashed broken lines represent boundaries of the claimed design and form no part of the claimed design. The dotted broken lines represent disclosed but unclaimed subject matter and form no part of the claimed design.
